Primary Examiner — Cynthia Ramirez*Assistant Examiner* — Gino Colan(74) *Attorney, Agent, or Firm* — Mei & Mark LLP(57) **CLAIM**

The ornamental design for a valve housing, as shown and described.

DESCRIPTION

FIG. 1 is a first perspective view of a valve housing.

FIG. 2 is a second perspective view of the valve housing.

FIG. 3 is a front view of the valve housing.

FIG. 4 is a back view of the valve housing.

FIG. 5 is a right side view of the valve housing.

FIG. 6 is a left side view of the valve housing.

FIG. 7 is a top view of the valve housing.

FIG. 8 is a bottom view of the valve housing; and,

FIG. 9 is a third perspective view of the valve housing.

The broken lines in FIG. 9 of the drawings showing a membrane are included for the purpose of showing environmental features that form no part of the claimed design.

1 Claim, 9 Drawing Sheets(56)
